INVENTOR

UNITED STATES PATENT OFFICE

99,426

DESIGN FOR A HOSE FASTENER

Victoria Grace Corel, San Leandro, Calif.

Application June 30, 1934, Serial No. 52,411

Term of patent 3½ years

To all whom it may concern:

Be it known that I, Victoria Grace Corel, a citizen of the United States, residing at San Leandro, in the county of Alameda and State of California, have invented a new, original, and ornamental Design for a Hose Fastener, of which the following is a specification, reference being had to the accompanying drawing, forming part thereof.

I claim:

The ornamental design for a hose fastener, as shown.

VICTORIA GRACE COREL.
